UNITED STATES PATENT OFFICE.

ARTHUR MARSHALL McINTOSH, OF SYDNEY, NEW SOUTH WALES, AUSTRALIA.

MOUTH-GAG FOR SURGICAL PURPOSES.

No. 902,993.

Specification of Letters Patent.

Patented Nov. 3, 1903.

Application filed June 16, 1903. Serial No. 438,799.

To all whom it may concern:

Be it known that I, ARTHUR MARSHALL McINTOSH, a subject of the King of Great Britain, residing at 157 Macquarie street, 5 North, Sydney, in the State of New South Wales, Commonwealth of Australia, have invented new and useful Improvements in Mouth-Gags for Surgical Purposes, of which the following is a specification.

10 This invention has been devised with a view to provide a simple and effective apparatus which shall have the effect of opening the mouth of a patient and maintaining it in an open position while operations are 15 being performed in the interior of the mouth.

The invention comprises the novel features of construction and arrangement of parts hereinafter described and particularly set forth in the appended claims.

20 An embodiment of the invention is illustrated in the accompanying drawings in which—

Figure 1 is a side view of the whole appliance, the gag jaws being closed, the 25 hand plunger drawn out and the stop-cock open. Fig. 2 is a plan of the same. Fig. 3 is a similar view to Fig. 1, but the hand plunger has been forced into the cylinder, the jaws are open and the intermediate tap or 30 cock has been closed, thus maintaining the gag jaws in the open position.

A is the upper gag-jaw, B the lower one, and they are articulated together at the hinge a. The jaws A, B, are peculiarly 35 shaped each jaw is semi-circular to admit of the introduction between them of the hydraulic cylinder C and plunger C¹. The cylinder C is articulated at c to the lower jaw B and the plunger C¹ is articulated at c¹ to the 40 upper jaw A, so as to permit of a compensating relative adjustment when the jaws A, B, are opened.

Beyond the semi-circular shape of the jaws A, B, each jaw is returned back in a curve 45 (see Fig. 2) so that the jaws may be able to pass round the corner of the mouth and the tooth plates D, D¹ be inserted between the teeth or, in the absence of teeth, between the gums of the patient. In the latter instance 50 the tooth plates D, D¹ will be padded so that the serrated edges will not hurt the gums.

Articulated to the cylinder C, by a water-tight joint e is another cylinder E the upper 55 end of which constitutes a hydraulic ram, of which E¹ is the plunger. The plunger terminates in a button F whereby the plunger E¹

may be pushed down by the hand of the operator. In order to give a purchase the top end of the cylinder E is provided with finger pieces F¹ adapted to fit the first and second 60 fingers of the hand of the operator, while the button F will lie in the palm of his hand, in a manner that is well understood. At an intermediate point in the cylinder E is a stop-cock f. When the appliance is in the position shown in Figs. 1 and 2 the stop-cock f will be open, but when the plunger E¹ is pushed down the stop cock f will be closed, as in Fig. 3.

It will be remarked that the cylinder E is 70 much longer and of less diameter than the cylinder C, consequently, there is a great gain in leverage, thereby rendering the appliance better adapted to the work to be done.

In using the appliance, the tooth plates D, 75 D¹ are inserted between the teeth, or the gums, of the patient, the jaws A and B will then lie against his cheek, the button F of the hand ram being behind his head. The operator, with his hand, will seize the hand 80 ram in a manner that is well understood, will push down the ram E¹ the full distance and will then turn off the cock f. The effect of pushing down the ram E¹ will be that the jaws of the patient will be opened, and by 85 turning off the cock f they will be caused to remain in the opened position as long as desired by the operator.

Having now described my invention what I claim as new and desire to secure by Letters 90 Patent is:—

1. The improved mouth gag for surgical purposes consisting of an upper and lower jaw articulated together at the rear and turned inwards so that their ends can enter 95 the mouth of the patient, tooth plates projecting from the turned in ends of the jaws, and at right angles thereto, and a hydraulic plunger articulated to one jaw while a hydraulic cylinder is articulated to the other 100 jaw and means for operating the hydraulic part of the appliance as herein set forth.

2. In mouth gags for surgical purposes, in combination, two hinged jaws adapted to lie against the cheek of the patient the forward 105 ends of the jaws being adapted to enter the mouth of the patient, a hydraulic ram between the articulated jaws a long narrow hydraulic ram articulated to the cylinder element of the ram between the jaws and means 110 for operating the plunger of the long ram as specified.

3. In mouth gags for surgical purposes, in combination, two hinged jaws that are adapted to lie against the cheek of the patient the forward ends of the jaws being turned inwards and provided with tooth or gum plates at right angles, a hydraulic ram installed between the articulated jaws, the plunger being articulated to one jaw while the cylinder is articulated to the other jaw, a long hydraulic ram of small diameter articulated to the hydraulic cylinder between the articulated jaws, a plunger provided with a termi-

nal button and means for holding the appliance so that it may be manipulated with one hand of the operator and an intermediate stop cock in the long hydraulic cylinder as herein set forth. 15

In testimony whereof I have signed my name to this specification in the presence of two subscribing witnesses.

ARTHUR MARSHALL MCINTOSH.
